UNITED STATES PATENT OFFICE.

PAUL McDORMAN, OF NIAGARA FALLS, NEW YORK, ASSIGNOR TO THE ELECTRO-CHEMICAL COMPANY, OF DAYTON, OHIO, A CORPORATION OF OHIO.

ELECTROLYTIC CELL.

1,342,336.

Specification of Letters Patent.

Patented June 1, 1920.

Application filed June 19, 1919. Serial No. 305,241.

To all whom it may concern:

Be it known that I, PAUL McDORMAN, a citizen of the United States, residing at Niagara Falls, in the county of Niagara and State of New York, have invented certain new and useful Improvements in Electrolytic Cells, of which the following is a specification.

The principal object of my invention is to provide an electrolytic cell which produces a gas having a low percentage of impurities. With this end in view, I provide, among other things, an air-tight cell which is so thoroughly sealed that chlorin gas cannot escape when high pressure is put on the chlorin line, nor can air later enter the cell through breaks in the sealing material to lower the chlorin content of the gas produced.

Another object of the invention is to provide means in the cell which permits the hydrostatic head of the electrolyte to rise when the porosity of the diaphragm becomes lessened, thereby giving the same rate of flow through the diaphragm at all times.

Another object of the invention is to provide a hood for the cell, that prevents the air from getting to the hydrogen formed around the cathode.

Other important and incidental objects will be brought out in the following specification, and particularly set forth in the subjoined claims.

One form of embodiment of my invention is illustrated in the accompanying drawings, of which Figure 1 is a vertical sectional view taken through my improved cell, and Fig. 2 is a vertical sectional view of one top edge of said cell, showing the hood and gasket construction.

Throughout the specification and drawings, similar reference characters denote corresponding parts.

Referring to the accompanying drawings, the numeral 1 designates a perforated cylindrical iron cathode whose bottom rests in an annular channel 2 provided near the marginal edge of a base member 3. Also resting in the annular channel 2, is a cylindrical diaphragm 4 preferably constructed of asbestos or other suitable porous material. This diaphragm has a relatively tight fit in the cell against the interior por-

tion of the cathode 1. Spaced a short distance from the diaphragm 4, is a cylindrical anode 5 preferably constructed of graphite.

Between the upper end of the anode 5 and the diaphragm 4, there is placed a gasket 6 which curves outwardly to assume a horizontal position between the top of the cathode 1 and a gasket 6^a upon which rests the flat marginal portion of a dome-shaped head 7 for the cell. Bolts 8 pass through the horizontal top of said cathode, the gaskets and marginal portion of the head 7, to clamp them firmly together. On top of the marginal flat portion of the head 7 is the annular gasket 9 through which the bolts 8 pass, while on top of said gasket 9 there rests the inwardly projecting flange portion 10 of a cylindrical hood 11 that surrounds said cell. This hood 11, whose bottom portion rests in the channel 2 in the base 3, is provided to prevent air from getting to the hydrogen formed on the cathode, which would lower the efficiency of the cell. The bolts 8 also pass through the flange 10 on this hood, receiving on their top ends, nuts 12 by means of which the head 7, hood 11, cathode 1, annular gaskets 6, 6^a and 9, and the diaphragm 4, are firmly clamped together, to make an air-tight construction. Around the base portion of the hood, cathode and diaphragm, the electrolyte forms a seal in the channel 2 of the base 3.

Under the old method where putty and like substances are used to seal the cell, the chlorin when under high pressure in the chlorin line, will often break the seal, causing chlorin gas to escape into the room and thus interfering materially with the work. Later air will enter the cell through the breaks in the putty, resulting in a lowering of the chlorin content of the cell gas. My improved construction obviates these difficulties by the employment of annular gaskets which are firmly clamped between the cathode and head of the cell to thoroughly seal the latter against the escape of chlorin and the admission of air. Furthermore, the gasket 9 forms a tight seal between the hood 11 and head 7, while the gasket 6^a is pressed tightly between the anode 5 and said head by studs 13, said anode extending downwardly to a point a short distance above the base 3.

Salt brine is admitted to the cell through an inlet tube 14 fitted in a hole in the middle portion of the base 3. At the anode 5 chlorin gas is generated, which passes off through a tube 14^a fitted in a hole in the middle portion of the dome-shaped head 7.

The electrolyte passes through the porous diaphragm 4 into contact with the perforated iron cathode 1, where caustic soda is formed, said caustic passing through said cathode into the space between the latter and the hood 11, dropping down there-through into a caustic outlet tube 15 that communicates, through an insert 16, with the channel 2. (See arrows in Fig. 1.)

The iron cathode 1 and porous diaphragm 4 are held firmly against the inner wall of the channel 2, by a hoop 17. Although the perforated cathode 1 and porous diaphragm 4 are pressed against each other, caustic is formed between them by the electric current which is conducted through a bolt 8, as a terminal, to the cathode. Provided around the bolt 8 is a rubber sleeve 8^a to prevent a short circuit between the anode and cathode. The head 7 will act as a conductor to the graphite anode, doing away with the copper bushbar commonly used.

Communicating with the space between the cathode 1 and hood 11, through the cell head 7, is a vent tube 18 which permits hydrogen to escape.

The reason I prefer to employ a dome-shaped head for the cell is, that it permits the hydrostatic head of the electrolyte to rise when the porosity of the diaphragm becomes lessened by long usage or for other causes. As is well known in the art, this diaphragm is provided to prevent the products of electrolysis from mixing, chlorin being formed at the anode and caustic on the cathode. When the porosity of this diaphragm becomes lessened, the flow of electrolyte through it is retarded unless the hydrostatic head of the latter is raised. This is made possible by the dome-shaped head, which permits the level of the electrolyte to rise as the porosity of the diaphragm decreases, thereby insuring an even flow of liquor through the diaphragm at all times irrespective of the degree of porosity of the latter.

Having described my invention, I claim:

1. In an electrolytic cell, the combination with a base member, of a hollow cathode mounted thereon, an anode within said cathode above the base, a porous diaphragm between said anode and cathode, a head for said cell, and gasket means between said head and the anode and cathode, to

thoroughly seal said cell against the escape of chlorin and the admission of air.

2. In an electrolytic cell, the combination with a base member, of a cylindrical cathode mounted thereon, an anode within said cathode above the base, a porous diaphragm between said anode and cathode, a head for said cell, gasket means between the marginal portion of said head and the cathode and anode, and means for firmly pressing said marginal portion against the gasket, to thoroughly seal said cell against the escape of chlorin and the admission of air.

3. In an electrolytic cell, the combination with a circular base member having an annular channel in its top portion, of a cylindrical cathode resting in said channel, a porous diaphragm within said cathode, also resting in said annular channel, an annular gasket seated on the top portion of said cathode, a head for said cell having a flat marginal portion, a gasket between said marginal portion and the first gasket, an anode, means pressing said anode against the second gasket, and bolts passing through said cathode, gaskets and flat marginal portion of said head, firmly to clamp them together to seal said cell against the escape of chlorin and the admission of air.

4. In an electrolytic cell, the combination with a base member, of a hollow cathode mounted thereon, an anode in said cell, a porous diaphragm between said anode and cathode, and an upwardly bulging head for said cell, to permit the level of the electrolyte to rise when the porosity of the diaphragm is lessened.

5. In an electrolytic cell, the combination with a circular base member, of a cylindrical cathode mounted thereon, an anode in said cell, a porous diaphragm between said anode and cathode, and a dome-shaped head for said cell, firmly secured to the top of said cathode, to permit the level of the electrolyte to rise when the porosity of the diaphragm is lessened.

6. In an electrolytic cell, the combination with a base member, of a cylindrical cathode mounted thereon, an anode in said cell, a porous diaphragm between said anode and cathode, a head for said cell, and a hood secured to said head and surrounding the cathode to prevent the admission of air to the hydrogen formed on the latter.

In testimony whereof I have hereunto set my hand this 14th day of June, 1919.

PAUL McDORMAN.

Witness:

HOWARD S. SMITH.
